UNITED STATES PATENT OFFICE.

HUGH A. BARDEEN, OF LOS ANGELES, CALIFORNIA.

ROLLER-BIT.

1,238,707.

Specification of Letters Patent. Patented Aug. 28, 1917.

Application filed September 1, 1915. Serial No. 48,549.

To all whom it may concern:

Be it known that I, HUGH A. BARDEEN, a citizen of the United States, residing at Los Angeles, in the county of Los Angeles and

5 State of California, have invented a new and useful Improvement in Roller-Bits, of which the following is a specification.

My invention relates to the art of drilling oil wells or the like, and particularly to 10 that system of drilling commonly designated the "rotary system", in which a long column or string of drill pipe is rotated by means of a table located at the surface of the ground, the string of drill pipe carrying at 15 its lower end some sort of a cutting tool commonly designated as a "bit".

The first object of the invention is to provide a bit which will rapidly and economically cut away the bottom of the hole especially when working in very hard rock.

In the rotary system of drilling, a heavy mud is employed, this mud being forced downwardly through the string of drill pipe and emerging through holes placed at 25 or near the cutting portion of the bit. This mud is used for the purpose of carrying away the cuttings of the bit and also for the purpose of providing hydrostatic pressure and cementing means for retaining the walls 30 of the well.

It is common practice in the drilling art to employ a bit commonly designated as a "fish tail bit", this bit consisting of a flat body having a cutting edge at its lower end, 35 such bits having special efficiency in that the flat body tends to thoroughly mix the mud and to compact it and force it against the wall of the well. The flat body is also very efficient in guiding the cutting edges so that 40 a straight hole will be produced. The fish tail bits are objectionable, however, in that their action is a grinding one, and they do not work well in layers of hard rock, commonly termed "shells".

45 The second object of my invention is to provide a bit which will have a flat body adapted to guide the cutting members and to thoroughly mix the mud, and which at the same time will be provided with very 50 efficient cutting members, enabling it to drill much more rapidly than the fish tail bit. There have been produced in the past, and are now on the market, a considerable number of bits in which rolling cutters are employed. These bits are quite efficient, but are 55 costly to maintain due to the special form of

cutters employed and due to the fact that expensive oiling devices have to be provided for the purpose of preventing wear on the cutting members.

The third object of my invention is to provide a bit having a rotary cutting member which will be inexpensive to produce and replace and which will not require any special means of lubrication.

It has generally been assumed in the case of rolling cutters, that they should be designed in such a manner that there would be no rubbing action of the cutters on the bottom of the hole. The majority of inventors 70 who have attempted to produce roller bits, have attempted to use conical rollers so that the speed of travel on all parts of the roller would correspond to the movement of the bit at that point on the bottom of the well. 75 It is my present opinion that this theory is incorrect and that the cutters of the roller bit should be so designed that there is considerable rubbing action. It is true that this tends to wear the cutters, but it also tends to 80 give the bit a greater drilling capacity which is highly desirable.

The fourth object of the invention is to provide a bit in which the cutters not only roll on the bottom of the hole, but in which 85 certain parts of the cutters have an abrasive or cutting action tending to greatly increase the efficiency of the bit.

I have found that the most economical way to operate a roller bit is to provide a bit 90 which will have relatively inexpensive cutters which cut rapidly, thereby giving a bit of great capacity and which at the same time can be quickly and easily replaced at nominal cost.

The fifth object of the invention is to provide means for so securing the cutters of a roller bit that they can be readily removed and replaced.

I have also found that any oiling system is 100 expensive and troublesome, and the sixth object of the invention is to provide a bit which will operate without the necessity for any such special oiling device.

I have further found that there is a great 105 tendency for fish tail bits, or similar bits, having a flat body, to wear on their outer edges so that the usefulness of such body is greatly reduced after it has been in the well for a short time.

Further objects and advantages will be evident to one skilled in the art after an in-

spection of the attached drawing and a perusal of the following specification.

In the drawing, which is for illustrative purposes only:

5 Figure 1 is a view of the bit in use in an oil well, a portion thereof being shown in section to better illustrate the method of securing the bit to the lower end of the drilling string, and the method of attaching the cutters.

10 Fig. 2 is an enlarged section of a portion of the lower end of the bit with one of the cutters in place thereon.

15 Fig. 3 is a partial section on the line x^3-x^3 of Fig. 1 looking in the direction of the arrows.

20 In the drawing, 11 is the lower end of a tool joint or coupling secured to the lower end of the drilling string, the coupling 11 being threaded at 12 to receive a threaded projection 13 formed on the upper end of the body 14 of the roller bit. The side walls of the well are shown at 15, and the bottom of the well is shown at 16. The body 14 is 25 of elongated form, as shown, and of slightly smaller diameter than the desired bore of the well. Secured at either edge thereof is a removable strip 17 which is dove-tailed into the body 14 of the bit. A drilled hole 18 connects a pair of drilled holes 19 and 20 which extend upwardly from the lower edges 21 and 22 of the body 14 and communicate with a central hole 23 in the projection 12, which in turn registers with and connects to an open hole 24 in the coupling 30 11, which is in open communication with the interior of the string of drilling pipe. Secured to the lower end of the body 14 is a projection 25 slightly wider than the body 35 having two cylindrical pins 26 formed on either side thereof.

40 The pins 26 are machined to form smooth cylinders and the body of the bit is machined at right angles to the axis of the pins 45 to form shoulders 27. Each of the pins 26 has an opening 28 drilled therein, the outer end of the opening being threaded as shown at 29, and the inner end being smooth and of a somewhat smaller diameter than the 50 threaded portion 29. Threaded in the openings 28 are cap bolts 30. Each of these bolts has a head 31, somewhat larger in diameter than the pins 26, a threaded portion 32, fitting tightly in the threaded portion 29 of 55 the opening 28, a portion 33 of smaller diameter than the portion 32 and having a locking groove 34 cut therein, and a small end 35 which projects slightly through the projection 25 and fits into a small hole in an 60 inner washer 36. The inner washers 36 are placed on the pins 26 and are locked in place not only by the end 35 but also by the clamping action of a stationary bushing 37 which 65 is held in place by the clamping action of the cap bolts 30. An outer washer 38 is

placed between each of the heads 31 and the stationary bushings 37. The washer 36, the bushing 37, and the washer 38 form a removable stationary bearing surface for the cutters 40 and 41, loose bushings 42 turning 70 freely in the bore of the cutters upon the bushings 37. Pins 43 are driven through holes formed in the projection 25 engaging the grooves 34 and locking the cap bolts 30 firmly in place.

75 The pins 26 are inclined as shown in the drawing, at an angle of approximately 25° with the horizontal, the outer cutter 41 bearing on a conical surface 50 adjacent to the walls of the hole 15, and the inner cutter 40 bearing on an inner cone 51 having its apex at the center of the hole. As the bit is rotated the cutter 40 continually rolls upon and cuts the cone 51, and the cutter 41 continually rolls upon and cuts the cone 50.

80 The method of operation is as follows:

85 The drill pipe being rotated by any of the standard methods, and mud being forced downwardly therethrough, this mud passes through the holes 19 and 20, being forced downwardly over the cutters 40 and 41, these cutters rolling upon the bottom of the hole and cutting the cones 50 and 51 as previously described. The cutters in their preferred 90 form have a screw thread cut on the periphery thereof. The cutters wear relatively rapidly, but being of simple form they are cheap to produce and can be replaced at a very small expense. If desired transverse 95 cuts can be made across the face of the cutters 40 and 41 to produce a serrated cutting edge.

100 I find in practice that one set of bushings will outlast several sets of cutters. The pins 26 and 27 do not wear at all, being protected by bushings 37, and the washers 36 and 38 are readily replaced, these washers, however, wearing comparatively slowly. The long body 14 steadies the bit in the hole, 105 thoroughly mixes the mud, and greatly assists in digging through the relatively soft formations. The dove-tailed edges 17 are readily replaced as they become worn, so that the body 14 of the bit, which is the expensive portion, can be operated indefinitely, 110 the wearing parts all being replaceable.

115 The inclination of the cutters is very important, as it is practically impossible to place a cylindrical cutter in a well unless it is so inclined, due to the difficulty of reaching the outer edge of the hole with a cylindrical cutter. A cylindrical cutter can not be placed in a vertical hole, with its axis horizontal, in such a position that it will cut to the extreme wall of the hole. By using 120 cutters having the proportions shown in the drawing, it is possible to cut to the extreme wall of the hole and at the same time obtain sufficient clearance above to prevent rubbing 125 of the walls of the well above the bottom.

I claim as my invention:

1. A roller bit for use in an oil well comprising a body, an outer pin and an inner pin secured in said body at an inclination to the axis of the well, an outer cutter on said outer pin, and an inner cutter on said inner pin, said pins being so located that said outer cutter rolls on a path around the outer portion of the bottom of the well, and said inner cutter rolls on a path inside of the path of said outer cutter comprising approximately all of the remainder of the bottom of the well.
2. A roller bit for use in an oil well comprising a body, an outer pin and an inner pin secured in said body at an inclination to the axis of the well and approximately parallel with each other, an outer cutter on said outer pin, and an inner cutter on said inner pin, said pins being so located that said outer cutter rolls on a path around the outer portion of the bottom of the well, and said inner cutter rolls on a path inside of the path of said outer cutter comprising approximately all of the remainder of the bottom of the well.
3. A roller bit for use in an oil well comprising a body, an outer pin and an inner

pin secured in said body at an inclination to the axis of the well, a cylindrical outer cutter on said outer pin, and a cylindrical inner cutter on said inner pin, said pins being so located that said outer cutter rolls on a path around the outer portion of the bottom of the well, and said inner cutter rolls on a path inside of the path of said outer cutter comprising approximately all of the remainder of the bottom of the well.

4. A roller bit for use in an oil well comprising a body, an outer pin and an inner pin secured in said body at an inclination to the axis of the well and approximately parallel with each other, a cylindrical outer cutter on said outer pin, and a cylindrical inner cutter on said inner pin, said pins being so located that said outer cutter rolls on a path around the outer portion of the bottom of the well, and said inner cutter rolls on a path inside of the path of said outer cutter comprising approximately all of the remainder of the bottom of the well.

In testimony whereof, I have hereunto set my hand at Los Angeles, California, this 27th day of August, 1915.

HUGH A. BARDEEN.
